UNITED STATES PATENT OFFICE.

EDWARD D. MILLHOUSE, OF WABASH, INDIANA, ASSIGNOR OF ONE-HALF TO JOHN F. PYLE,
OF WABASH, INDIANA.

BURIAL-VAULT.

No. 921,554.

Specification of Letters Patent.

Patented May 11, 1909.

Application filed November 17, 1908. Serial No. 463,076.

To all whom it may concern:

Be it known that I, EDWARD D. MILLHOUSE, a citizen of the United States, and a resident of Wabash, in the county of Wabash and State of Indiana, have invented certain new and useful Improvements in Burial-Vaults, of which the following is a specification.

My invention is an improvement in burial vaults and consists in certain novel constructions and combinations of parts hereinafter described and claimed.

Referring to the drawings forming a part hereof, Figure 1 is a perspective view of the vault with the cover elevated, Fig. 2 is a transverse section through the vault, and Fig. 3 is a perspective view of the reinforcing frame.

The present embodiment of the invention comprises a box 1, and a cover 2, both formed of plastic material capable of hardening, and having embedded within the substance thereof, a reinforcing metallic frame to be presently described in detail.

The reinforcing frame of the box proper consists of a plurality of U-shaped strips 3, connected at suitable intervals by longitudinal strips 4, which strips are continued across the ends of the box. The longitudinal strips are practically continuous, being formed of a single bar whose ends are riveted together. The reinforcing frame of the cover consists of a plurality of U-shaped strips whose body portion is of angular shape, as shown at 6, 35 the arms being flat, and connected by longitudinal strips, 7, which may be continuous as described for the strips 4. The body portions are also connected by a longitudinal strip 8. To the end U-shaped strips 5, are connected the shanks 9 of rings 10, which rings are adapted to receive the straps for lowering the cover into the grave. The shanks are riveted to the angular portion of the strips as at 11, and near each end of the same. The box is provided on its outer face with a ledge or rib 12, which is continuous and spaced apart a distance below the edge 13 of the box, and the upper face of the ledge is inclined inwardly and downwardly as at 14, to form a trough which encircles the box.

The cover is flanged as shown at 15 and

the lower edge of the flange is inclined upwardly and inwardly as shown at 16, in such manner that when the cover is placed in position on the box, a space is formed 55 between the free edge of the flange and the upper face of the ledge extending entirely around the vault and triangular in cross section. The flange is of a depth such that when the cover rests upon the free edge of 60 the box, the said flange will reach the upper face of the rib, but will not press thereagainst, the edge of the flange and the upper face of the rib abutting.

When in use, after the box is placed within 65 the vault, plastic material is placed upon the ledge, and the cover is lowered into place. The weight of the cover forces the free edge of the flange into the plastic material, which is forced into all the crevices, thus effectually 70 sealing the vault.

It will be observed that the weight of the cover is supported by the free edge of the box and not by the fresh plastic material resting upon the ledge, and that the fresh 75 plastic material is prevented from displacement by the over hanging outer edges of the flange, and of the rib.

I claim:

1. A vault of the class described, comprising a box having an external ledge or rib parallel with the free edge thereof, and spaced apart therefrom, the upper face of the ledge or rib being inclined inwardly and downwardly to form a trough, and a cover 80 provided with a flange fitting outside of the walls of the box, said flange being of lesser depth than the distance from the edge of the box to the ledge or rib and inclined inwardly and upwardly whereby when the cover is in place an annular recess closed on 85 its outer side will be formed between the edge of the box and the edge of the flange.

2. A vault of the class described comprising a receptacle, and a cover of plastic 95 material, said cover having a reinforcing frame composed of U-shaped strips whose arms are flat, and whose body portion is of angle material, and rings provided with shanks riveted to the angular part of the 100 body portion near the ends thereof, and extending through the plastic material, and

longitudinal strips connecting the arms of the U-shaped strips.

3. A vault of the class described, comprising a receptacle, and a cover of plastic material, said cover having a reinforcing frame composed of U-shaped strips whose arms are flat, and whose body portion is of angle material, and rings provided with

shanks riveted to the angular part of the body portion near the ends thereof, and extending through the plastic material.

EDWARD D. MILLHOUSE.
